UNITED STATES PATENT OFFICE.

GREGORY SMITH WOODFORD, OF LOS ANGELES, CALIFORNIA.

CYLINDER-FORMING MACHINE.

Application filed June 6, 1927. Serial No. 196,903.

My invention relates to machines used in the manufacture of cylindrical paper cups or containers for frozen confections. Such machines employ a rotating mandrel on which the cup-forming paper is wound so that a portion thereof will lap over an end of the mandrel; this lapped portion is turned over the end and flattened down to constitute the bottom of the container. In order to compress the folded-over end of the paper and pack it against leakage considerable pressure is required. Heretofore it has been the practice to employ a presser member on a swinging carrier that can be brought into 10 pressing relation with the end of the mandrel at proper intervals, and since the presser does not turn with the mandrel a twist is given to the folded over paper at the same time that pressure is applied to flatten and 15 compact the same. Practice has demonstrated that with a non-rotatable presser the edges of the paper, due to the twisting action and the tendency of the paper edge to catch, become torn, more or less, which causes 20 the cream filler to leak through.

The principal object therefore, of my invention, is to overcome this objectionable feature and to that end I provide a presser member composed of a non-rotatable central 25 portion and a rotatable annular portion, thus providing a structure in which that part of the presser which contacts the edge of the container rotates with the container and mandrel while that part which is required 30 to give the twist-pressure to the folded over paper remains stationary.

Further, it is an object of the invention to provide a means to improve the structure 35 of the container by effecting a better sealing of the bottom without the necessity of additional operations beyond those now employed.

Generically the invention resides in the novel construction, combination and arrangement of parts, which will be hereinafter described, and then pointed out in the appended claims, reference being had to the accompanying drawing, in which:

Figure 1 is a side elevation of a portion 50 of a paper cylinder machine showing the rotatable mandrel mounted in its bearing, a paper cup being shown (parts of the cup being broken away) and with the presser about to be brought into action.

Figure 2 is a vertical longitudinal section 55 (parts being shown in elevation) showing

the presser in position, the paper cup being indicated in dotted lines.

Figure 3 is a detail vertical longitudinal section and part elevation of a slight modification of the invention.

Figure 4 is a perspective view of the presser unit of Figure 3 per se.

In the drawing in which parts performing the same function and having the same relation to other parts bear the same reference numbers, the mandrel 1 is shown journaled in a suitable bearing 2 and provided with a gear portion 3 that may mesh with the driving gears (not shown) by means of which the rotating motion is given to the mandrel on its central axis. The mandrel 1 has its outer end cupped as at 4 to receive the cup end 6 of the ejector, the rod 5 of which passes through the mandrel and is 75 operated, at suitable intervals, by mechanism (not shown) to eject or strip container from the mandrel.

An arm 7, pivoted at 8, is turned on its pivot by suitable mechanism (not shown) operating at timed intervals to bring the presser head into and remove it from relation with the mandrel. The presser head of my invention comprises a stud having a stationary head 9, constituting the stationary 85 presser plate, a shank 10 with reduced threaded end forming a shoulder 11 to abut the arms 7 through which the threaded end passes and is secured by a nut.

Rotatably mounted on the head 9 and shank 10 (see Figure 2) is the rotatable presser member 13. This member 13 is recessed at 14 to receive the head 9 so that the pressing face of the head 9 and the corresponding face of the member 13 will be 90 flush. The rotatable head member 13 is held in place by a spring 19 as indicated in Figures 1 and 2 of the drawing.

Instead of applying the spring 19 over the hub 15 into direct contact with the presser 100 member 13, a disk 18 having a ball race registering with a ball race 16 in the rotatable head 13 is provided, balls 17 being located in the races to reduce friction (see Figure 3).

The operation, so far as the timing of the movements of the mandrel, the ejector and the presser are concerned, does not differ from previous practice. However, since the member 13 can turn with the mandrel 110 through its frictional engagement with the paper, all danger of tearing the paper at

the folded over edge is eliminated; the direct pressure of plate 9 and the pressure applied via spring 19 to the rotatable head member 13 serve tightly to compact the 5 folded over paper and render the same proof against leakage when the content is placed in the cylindrical container.

From the foregoing description, taken in connection with the accompanying drawing, 10 it is thought the construction, operation and advantages of my invention will be clear to those skilled in the art to which it relates.

What I claim is:

- 15 1. In paper cylinder forming machines in which a rotatable mandrel cooperates with a presser to form the cylinder with a closed end; a presser comprising a head having a non-rotatable face portion and a rotatable face portion.
- 20 2. In paper cylinder forming machines in which a rotatable mandrel cooperates with a presser to form the cylinder with a closed end; a presser comprising a stud having a pressing face, means holding said stud against rotation and adapted for carrying said presser to and from cooperative relation with the mandrel, and a rotatable member carried by the stud and having a pressing face cooperating with the pressing face 25 of said stud, and means to hold said rotatable member in place on said stud.
- 30 3. In paper cylinder forming machines in which a rotatable mandrel cooperates with a presser to form the cylinder with a closed end; a presser comprising a stud having a pressing face, means holding said stud against rotation and adapted for carrying said presser to and from cooperative relation with the mandrel, and a rotatable member carried by the stud and having a pressing face cooperating with the pressing face 35 of said stud, and means to hold said rotatable member in place on said stud, said means comprising a head on the stud, a recess in said rotatable member for said head, and a spring for holding said rotatable member against said head.
- 40 4. In a machine for forming paper cylinders with closed ends, the combination with a rotatable mandrel, of a combined rotatable-section and non-rotatable-section presser for the purposes described.

5. In a machine for forming paper cylinders, a rotatable mandrel having a cupped end, a presser adapted to be brought into 55 and removed from cooperative relation with said cupped end and itself including means to press the paper of the folded over edge into the cup in a direction substantially parallel with the axis of the mandrel, and 60 also including means to impart a twisting pressure to the central part of the paper within the cup whereby the major portion of the twist of the paper will be given at the center of the cup.

6. In a machine for forming paper cylinders, a rotatable mandrel over one end of which the paper is adapted to be folded, a presser member for pressing the folded over paper tightly together to form the bottom 70 of the cup, said presser member having an annular rotatable portion adapted to rotate with the cylinder and a central non-rotatable portion for the purposes specified.

7. As a new article, a presser member for 75 paper cylinder forming machines which comprises a stud having a head and a shank, a ring-like head member mounted on said stud and countersunk to receive said head of the stud, whereby the face of the stud and the corresponding face of said ring-like head member will register, and a coil spring 80 on the stud for pressing said ring-like head member toward the head of the stud and continuously tending to maintain the registering faces of stud and ring-like head member in the same plane.

8. As a new article, a presser member for 85 paper cylinder forming machines which comprises a stud having a head and a shank, a ring-like head member mounted on said stud and countersunk to receive said head of the stud, whereby the face of the stud and the corresponding face of said ring-like head member will register, and a coil spring on 90 the stud for pressing said ring-like head member toward the head of the stud and continuously tending to maintain the registering faces of stud and ring-like head member in the same plane, and anti-friction bearing members interposed between said spring and said rotatable ring-like head member.

GREGORY SMITH WOODFORD.
